GARMENT

Jacob L. Alberts, Yonkers, N. Y., assignor to
Arthur S. Alberts, New York, N. Y.

Application October 14, 1932, Serial No. 637,740

9 Claims. (Cl. 2—42)

This invention relates to garments for women and has for its object to provide a body garment such as a brassière, corset or the like, which requires no shoulder straps to maintain it in place 5 over the bust.

It has heretofore been proposed to make garments of this character without shoulder straps by providing a tight fastening encircling the body above the bust, but such garments have not proven 10 successful, primarily because they are unsightly and also because a tight encircling binding at this point involves greater discomfort than the shoulder straps for which it is substituted.

The principal object of my invention is to provide 15 garments of the class described, and analogous garments, which although indistinguishable in appearance from similar garments of ordinary design, except for the absence of shoulder straps, will nevertheless retain their position on the body 20 in all positions of the latter, even when the garment is cut in the rear with the low back effect now in vogue.

A further object of the invention is to provide 25 a garment of this class wherein the garment is held in place in the manner described without confining the breasts to any greater extent than customary with a garment of like character having 30 made of any soft material now employed for garments of like character, such as silk, lace, net and the like.

A further object of my invention is to provide 35 a garment of the kind described with means for holding it in place, which means is entirely concealed within the seams of the garment, the seams being of no greater width than customary in garments of like character.

In the accompanying drawings I have illustrated 40 my invention as applied to several different types of garments, but it is to be understood that the invention is equally applicable to garments other than those selected for illustration.

In the said drawings:

Fig. 1 shows typical brassières embodying my 45 invention as it appears when not in use;

Fig. 2 is a similar view but showing the relative 50 position of the parts when tension is applied to the belt of the garment as when worn;

Fig. 3 shows the inner side of a portion of the 55 garment as illustrated in Fig. 1 but on an enlarged scale, to better show the character and position of the holding member;

Fig. 4 shows one of the holding members removed from the garment in the position it assumes when the garment is in use;

Fig. 5 is a sectional view on line 5—5 of Fig. 4;

Fig. 6 is a view similar to Fig. 4 but with the holding member in the position it assumes when removed from the garment and relieved of all tension;

Fig. 7 is a similar view but with the holding 5 member turned through an angle of 90°;

Fig. 8 is a perspective view showing the garment 10 illustrated in the preceding figures as appears when worn;

Figs. 9 and 10 are front and rear views, re- 15 spectively, showing my invention applied to a garment of the corset or girdle type; and

Fig. 11 is a view similar to Fig. 2 showing my 20 invention applied to another type of brassière.

In Figs. 1 to 8 I have illustrated my inven- 25 tion as applied to a brassière of the bodice type. As here shown, 1 indicates the belt of the garment which, as is customary in garments of this kind, encircles the body of the wearer below the breasts but above the waist line (see Fig. 8). This belt 30 portion is provided at the back with fasteners 2 as indicated, and with an elastic extension 4 and elastic inserts 3 to insure a snug fit.

The upper part of the garment may also be 35 of the usual construction comprising a covering for the bust having side portions 5 individually shaped to enclose the breasts of the wearer. The shaped portions 5 are made up in the usual fashion and beyond the shaped portions are the rear- 40 wardly extending portions 6 of generally triangular shape and connected to the portions 5 of the garment along a seam 7 which curves upwardly and outwardly from the belt portion of the garment, and thence inwardly over the top of the breasts. The lower edges of the shaped portions 45

5 are connected to the belt by a base seam 8 which extends along the top of the belt across the front under the other shaped portion 5 to a point where it connects with the other side portion 6. The belt 1 is shaped to project upwardly between the shaped portions 5, and the fabric of the garment constituting the shaped portions is made full so that each shaped portion assumes a convex semi-spherical contour when pressed outwardly.

On the inside of the seam 7 which extends 50 from the belt around the outside of the shaped portions, there is sewn a narrow tape 12, shown partly removed in Fig. 3, to provide an invisible enclosure for a wire spring 13 of the shape shown in Figs. 4 to 7 inclusive. This wire is of circular cross section and each end is bent back upon itself to form a rounded loop 14 which will not penetrate through the cloth of the enclosing pocket. This wire is quite elastic but not stiff in 55

the sense that a corset stay is stiff. It is curved, as shown, in two directions. That is to say, considering first a straight wire, it is bent to the form of a flat arch, as shown in Fig. 6, all points 5 along the length of the wire, however, lying in a single plane. The wire at the middle is then bent laterally with respect to the ends of the wire in a direction transverse to the plane of the wire after the first bend, as indicated in Fig. 5, the 10 double curve of the wire resulting in the shape shown in Fig. 7. In the manufacturing on a commercial scale the wire is of course bent in a single operation and the resulting wire consists of a middle portion 8 curved on a flat arc, the 15 contiguous portions 9 continuing in the same arc but also bent to a lesser extent laterally from the plane of the middle portion, and extreme end portions 10 continuing in the direction of the curve of the arc but also extending more 20 nearly in a plane parallel with the plane of the middle portion.

The wire 13 is substantially equal in length to the seam 7 from the point of connection with the belt portion of the garment to the point on 25 the upper edge of the shaped portion immediately over the middle thereof. That is to say, the wire encircles the outer half of the shaped portion and is fully concealed within the seam 7.

When the garment is not drawn together and 30 fastened in the rear the curve of the wire is such as to lift the shaped portions of the garment above the position it will assume when the garment is on tight, as shown in Figs. 1 and 2. That is to say, the arc of the wire is flatter than 35 the curve of the seam 7 and tends to stretch the same out, shortening the upper marginal edge of the garment so that when the garment is fastened around the body of the wearer in the intended manner, the upper margin of the garment 40 will be drawn down, causing the spring to bow into substantially circular form, conforming with the contour of the seam and encircling the breast along the outer side.

The lateral bend imparted to the wire in the 45 manner described causes the wire, when placed under tension in the manner described, to substantially conform to the contour of the body and as the wire at the lower end and that portion of the base seam is held in substantially fixed position by reason of its attachment to the snugly 50 fitting belt the wire will be held in position following the curve of the body around the base of the breasts and thus hold the garment in precisely the position it would be held by a shoulder 55 strap attached to the garment in the usual manner, at about the point where the upper end of the wire terminates. The wire is flexible so as to bend readily when the garment is fastened, and is yet stiff enough to hold up the light 60 weight of the garment by reason of the tension under which it is placed when the garment is fastened.

It will be understood that the garment is 65 not drawn tight across the top over the breasts. The upper edge of the garment has considerably greater fullness than the belt portion but is held smooth and close to the body by the tension of the springs 13, which are highly elastic and bow to a greater or less extent as the movements 70 of the body require.

The double curve in the spring tends to hold 75 the upper edge of the garment snug over the breasts even when bending over forwardly, to a much greater extent than the usual shoulder straps. The reason is that in bending forward

the distance from the shoulder to the waist is considerably shortened, thus allowing the garment suspended from the shoulders to hang away from the body, whereas with my improved garment the upper edge will be pushed further up toward the shoulder and will continue to be held snug against the body.

The springs 13 may be fastened permanently in the seams 7 or may be made removable, as indicated in Fig. 3. As here shown a small opening 10 15 is provided on the upper edge of the seam 7 at the point where the end of the spring comes. The spring is readily inserted through the small opening and may likewise be readily withdrawn, as will be obvious.

In Figs. 9 and 10, I have shown my invention as applied to a garment of the corset or girdle type. Such a garment fits tight around the body only up to the waist, as indicated in Fig. 10, which shows a rear view of a wearer of this type 20 of garment. As will be obvious from this figure, the garment may be cut very low in the back, even below the bottom line of the brassière, without interfering with the fit of the garment in front.

Fig. 11 shows my invention applied to the bandeau type of brassière. In a garment of this type only the bottom hem fits snugly around the body, the slack in the upper edge of the garment being taken up by the elasticity of the 30 springs 13. As garments of this type are not usually worn by women of heavy figures, a very light, flexible spring 13 will be sufficient to hold the top of the garment in position against the body of the wearer.

It will of course be understood that my invention is not limited to the particular forms herein shown and described, but may be variously modified within the scope of the appended claims.

I claim:

1. A garment of the class described having a pair of breast pockets, a body-encircling portion beneath said pockets, and a pair of spring wires, said wires extending from the body-encircling portion, at respective positions beneath each breast pocket, upwardly around the outer side edges of said pockets and terminating at substantially the top centers of said pockets for holding the pockets in position, when the garment is worn, without the aid of shoulder straps.

2. A garment of the class described having a pair of breast pockets, a seam extending around the outer edge of each pocket from the bottom to the top, and an elastic spring wire in each of said seams for holding the pockets in position, when the garment is worn, without the aid of shoulder straps, said wire extending upwardly from a position at the bottom of said pockets around the outer edges thereof and terminating at substantially the top centers of the pockets and being held in bowed form under tension by the garment when the garment is being worn.

3. A garment of the class described having a pair of breast pockets, a curved seam extending around the outer side of each pocket from the bottom to the top, an elastic spring within each of said curved seams and extending from the bottom upwardly around the outer side edges of the respective pockets and terminating at substantially their top centers, the ends of said springs being spaced apart a distance sufficient to elongate the pockets vertically when the garment is not being worn, and body-encircling band portions extending from the outer side edges of the pockets, whereby when the garment is worn and

5 tension is placed on said bands the ends of the springs will be deformed towards each other and the upper front edge of the garment will be placed under tension and caused to lie against the body of the wearer.

10 4. A garment of the class described having a pair of breast pockets, a body-encircling portion beneath said pockets, a pair of curved seams, said seams extending respectively from the body-encircling portion at positions at the bottom of each breast pocket upwardly around the outer edges of said respective pockets to the top edges thereof, a spring wire within each of said curved seams and extending from the bottom upwardly around the outer side edges of the respective pockets and terminating at substantially their top centers, the ends of said wires being spaced apart a distance sufficient to elongate the pockets vertically when the garment is not being worn, 15 and generally triangularly shaped portions extending outwardly from the outer edge of each pocket and secured along their lower edges to said body-encircling portion, said body-encircling portion and the triangular portions extending from the outer edge of the pockets being adapted 20 to fit the body snugly, when the garment is worn, to hold it in position upon the wearer and to cause the ends of the spring wires to be deformed towards each other and that portion of the upper front edge of the garment between the upper ends of the springs placed under tension and caused to lie against the body of the wearer.

25 5. A garment of the class described having a pair of breast pockets, an elastic spring wire extending from the bottom of each pocket upwardly around the outer edge of each pocket and terminating at substantially the top center for holding the pockets in position, when the garment is worn, without the aid of shoulder straps, said wire being held in bowed form under tension when the garment is being worn.

30 6. A garment of the class described having a pair of breast pockets, a comparatively flexible, highly resilient, spring wire extending from a point adjacent the bottom of each pocket upwardly around the outer side edges to a point adjacent the top of each pocket, the ends of said spring wires being spaced apart when the garment is not being worn a distance exceeding the greatest vertical dimension of the pockets when the garment is worn, a body-encircling band portion extending at least in part from the outer side edges of the pockets, whereby when the

garment is worn and tension is placed on said band, the ends of the spring wires will be deformed towards each other and the upper front of the garment will be placed under tension and caused to lie against the body of the wearer.

35 7. A garment of the class described having a pair of breast pockets, each of which has an arched upper edge, a body-encircling portion beneath said pockets, a spring wire extending from the body-encircling portion and following the outer marginal edge of each pocket upwardly around said edge to substantially the top of each pocket, for at least in part holding the pockets in position against the body of the wearer when the garment is worn without the aid of shoulder straps, and a rearwardly extending connection 40 between the outer side edge of each pocket and the body-encircling portion for deforming the spring wire and thereby assisting in holding the upper portion of each pocket in position upon the body of the wearer when the garment is worn and tension is placed upon the body-encircling portion.

45 8. A garment of the class described having a pair of breast pockets, each of which has an arched outer edge, a body-encircling portion beneath said pockets, a seam extending around the outer marginal edge of each pocket, a spring wire located in said seam and following the outer marginal edge of the pockets upwardly around said edge to substantially the top of each pocket, for at least in part holding the pockets in position against the body of the wearer when the garment is worn without the aid of shoulder straps, and a rearwardly extending connection 50 between the outer side edge of each pocket and the body-encircling portion for deforming the spring wire and thereby assisting in holding the upper portion of each pocket in position upon the body of the wearer when the garment is worn and tension is placed upon the body-encircling portion.

55 9. A garment of the class described comprising a covering for the breasts, an elastic spring wire carried by said garment at the sides of the breast-covering portion, said wire being normally curved to a bowed position in one plane and also curved in a plane transverse to said first-mentioned plane to thereby hold the upper margin of the aforesaid garment portion against dropping downwardly or away from the body.

JACOB L. ALBERTS.
